UNITED STATES PATENT OFFICE.

EDGAR M. CLARK, OF NEW YORK, N. Y., ASSIGNOR TO STANDARD DEVELOPMENT COMPANY, A CORPORATION OF DELAWARE.

ART OF DISTILLING PETROLEUM OILS.

Application filed April 24, 1920. Serial No. 376,252.

To all whom it may concern:

Be it known that I, EDGAR M. CLARK, a citizen of the United States, residing at New York, in the county of New York and State 5 of New York, have invented a new and useful Improvement in the Art of Distilling Petroleum Oils, of which the following is a specification.

The present invention relates to the distillation of petroleum or hydrocarbon oils and will be clearly understood from the following description, illustrated by the accompanying drawings, in which

Figure 1 is an elevation of a device embodying the present invention, partially in section, and Figure 2 is a detail view of a portion thereof.

Frequently in the dry or fire distillation of petroleum oils, a residue of liquid is left 20 in the stills, which is removed and separately treated in a different still. This is particularly true in the case of pressure distillation of petroleum oils such as those of the fuel oil class, for the production of lighter oils, 25 such as gasoline, as has been described, for example, in the patent to William M. Burton, No. 1,049,667 of January 7th, 1913. At the termination of a dry distillation of a hydrocarbon oil, and particularly of such a 30 pressure distillation, the residual body of oil in the still and the setting of the still itself contain large quantities of heat which, in accordance with the present invention, may be utilized for the further treatment of the 35 residues of distillation.

Referring more particularly to the drawings, the numeral 5 indicates a drum, serving as a container for a bulk supply of oil which is to undergo distillation. Below this 40 drum are a number of downwardly inclined tubes 6, which are mounted within the setting 7 of the still in such manner as to receive the direct heat of the combustion gases. A deck 8 is provided above the tubes 45 and below the drum 5 in order to protect the latter from the direct heat of the furnace in the setting. The tubes 6 communicate at their upper and lower ends with the headers 9 and 10, respectively, and these headers 50 communicate with the drum 5 by the vertical pipes 11 and 12, the arrangement being preferably such that the communicating pipes enter the drum at points near the opposite ends of the latter. The drum is provided 55 with a vapor line which preferably has the

form of an inclined, lagged pipe 13 and communicates at its upper end with a suitable condenser, such as the air condenser 14. The lagged pipe 13 and the condenser 14 serve for the reflux or return of condensate heavier than the desired products of the distillation process proper, to the drum 5. A vapor line from the condenser 14, indicated by numeral 15, passes off to a condenser (not shown) for the condensation of the end products of distillation.

In the normal operation of the still the drum and tubes are charged with the stock to be subjected to distillation, and the still is fired in order to heat up and distill the charge. 70 A pressure of from 4 to 5 atmospheres may be maintained through the system. During the distillation, heat is continually supplied in the required amount and the oil circulates from the drum through the tubes 6 and back 75 to the drum. The vapors evolved from the oil pass off through the dephlegmator pipe 13 to the dephlegmating condenser 14 where products heavier than the desired end products are condensed and returned to the drum, 80 while the end products, with any lighter or incondensable vapors, pass off through the vapor line 15 to suitable condensers.

At the termination of the distillation, a residue remains in the drum 5 and in the 85 tubes 6, which is at a high temperature and which, particularly in the case of pressure distillation, contain considerable proportions of constituents, the boiling points of which are not greatly above those of the end 90 product of the distillation process proper. The still and setting are likewise at a high temperature, that of the setting being say, 1300-1500° F. The fires may then be drawn and the residue treated by the contained heat 95 of the still and the setting, in accordance with the present invention, as follows: An inert gaseous medium, such as steam, may be introduced into the still. It is preferred that the steam be introduced in an upward 100 direction into the circulating leg 11 between the upper header 9 and the drum, as thereby an active circulation of the residue from the drum thru the tubes and back to the drum is promoted. A 105 steam pipe 16 may enter the drum, and pass down into the header pipe 11, terminating in an upwardly directed nozzle or opening, thru which steam is injected into the oil. The gaseous medium introduced passes out 110

thru the vapor line, carrying with it a large proportion of vapors of the residual oil within the still. To the bottom of the dephlegmator condenser 14 a pipe 17 is connected which leads to the collectors and condensers 18 and 19. The vapors of oil and the steam, if the latter be used as the gaseous carrying medium, are condensed in the dephlegmator 14 and, the communicating valve 20 in the pipe 17 being open, the condensate thus formed is allowed to pass off to the collectors 18 and 19, and are not returned to the drum 5. A dephlegmation of the heavier fractions of the residue occurs in the lagged run back 13. The condensed water may be separated from the oil in the usual manner. In the case an inert gas other than steam is used, such as carbon dioxide or natural gas, the permanent gas passes off thru the vapor line 15 while the oil vapors carried by it condense in the dephlegmator 14 and pass off into the receptacles 18 and 19. The passage of the steam or the gaseous vehicle into the oil in the still is continued until the residues therein have been reduced to the desired consistency or until the contained heat of the still and settings are exhausted. In the treatment of the residues of pressure distillation of an oil having the character of fuel oil, the residues having a density of about 20 degrees Bé., about 60 per cent may be distilled off in accordance with the present invention as a gas oil of about 35° Bé. leaving in the still a final residue of tarry consistency, which may be removed thru the draw-off pipe 21.

I claim:

1. The process of utilizing the contained heat of a fire-heated still and setting at the

end of a pressure-distillation of a heavy oil 40 for the production of gasoline for the treatment of the residues of the distillation, said residues being of about 20 degrees Bé. density, which consists in withdrawing the still fire, subsequently passing steam thru the residues and condensing the evolved vapors until about 60 per cent of the oil of the residues have been removed and condensed, and withdrawing the residual oil from the still. 45

2. The process of utilizing the contained 50 heat of a fire-heated still and setting at the end of a pressure distillation for the treatment of the residues of distillation which consists in withdrawing the still fire, circulating the said residues thru a confined path 55 in the highly heated portions of the setting, injecting a gaseous medium into the said residues in such manner as to promote a circulation of the residues thru said path, withdrawing the gaseous medium together 60 with the oil vapors carried thereby, and condensing the oil vapors.

3. The process of utilizing the contained 65 heat of a fire-heated still and setting at the end of a pressure distillation of petroleum oils process for the treatment of the residues of distillation which consists in withdrawing the still fire, subsequently passing thru the body of the residue a gaseous vehicle, withdrawing the vapors of said gaseous vehicle 70 together with the oil vapors carried thereby, condensing and returning to the still the heavier portions of the oil vapors carried by the gaseous medium, and condensing and collecting the lighter portions of the said 75 oil vapors, these portions being heavier than the products of the initial distillation.

EDGAR M. CLARK.
